UNITED STATES PATENT OFFICE.

CLAUD G. CARLEY, OF COLORADO, TEXAS.

REBOILER.

969,037.

Specification of Letters Patent. Patented Aug. 30, 1910.

Application filed December 15, 1909. Serial No. 533,144.

To all whom it may concern:

Be it known that I, CLAUD G. CARLEY, a citizen of the United States, and a resident of Colorado, in the county of Mitchell and State of Texas, have invented certain new and useful Improvements in Reboilers, of which the following is a specification.

My invention relates to devices for reboiling water which has been condensed, preparatory to making artificial ice, and it consists in the combinations, constructions and arrangements herein described and claimed.

An object of my invention is to provide a device in which the water may be boiled by means of steam from the main boiler, for the purpose of driving out the air which is detrimental to the formation of the ice.

A further object of my invention is to provide a device in which the condensed water may be delivered into the boiler at a temperature close to the boiling point, thereby conserving the heat necessary to raise it to the boiling temperature.

A further object of the invention is to provide means by which the condensed water may be divided into fine streams, which, together with the high temperature to which it is subjected, aids in driving out the air.

Other objects and advantages will appear in the following specification and the novel features of the device will be particularly pointed out in the appended claim.

My invention is illustrated in the accompanying drawings, in which:

Figure 1 is a central longitudinal section through the device; Fig. 2 is a plan view of the device, the top being removed; and Fig. 3 is a transverse section through the device.

In carrying out my invention, I provide a receptacle A preferably of a rectangular shape, such as that shown in the drawings. This receptacle is in the nature of a pan and may be constructed of any suitable material. In the present instance, I have shown it as being made of metal. The pan is provided with a top B which has an offset bottom flange b arranged to contact with the upper edge of the pan A so as to make a tight fit. The cover B is provided with chimneys or pipes C.

The means for heating the water is shown in Figs. 1 and 2, and consists of a pipe D provided with a cock d. This pipe enters one end of the tank and is looped in the manner best shown in Fig. 2, being raised from the bottom of the tank, as shown in Fig. 1.

The coil passes from end to end of the pan and then is bent upwardly at d² and the return portion of the pipe d³ lies just underneath the top of the cover. The return portion is provided with a valve or cock d⁴. A spraying device E communicates with the pipe d³ at e. Also communicating with the spraying device are the pipes F, G and H. The latter pipe leads directly from the reservoir (not shown) holding the condensed water. The pipe F leads to the exhaust of the engine (not shown), while the pipe G leads to the exhaust and is for the purpose of conveying the exhaust steam to the spraying device E.

At one end of the pan A is a reservoir K. Projecting through the bottom of the pan A is a pipe L. This pipe extends upwardly and is provided with a valve M which is adapted to close the end of the pipe, being normally held in an open position by a float W. When the water falls to a predetermined level, the sinking of the float closes the valve. The reservoir or tank K is provided with a small receiving tray T on its exterior and has communication with this tray by means of an opening t. A drain pipe t' extends from the bottom of the tray T to a sewer. At the bottom of the tank K is a drain pipe k for emptying the tank K when necessary, and on the opposite side is a pipe k' which leads to the cooling coil (not shown) which is connected with the freezing tank. One end of the pan A rests upon the reservoir K, while the opposite end is supported by the legs P.

From the foregoing description of the various parts of the device, the operation thereof may be readily understood. Either live steam or exhaust steam may be used for heating the condensed water. In the former case, the cock d of the pipe D is opened, thereby permitting the steam from the main steam boiler to enter the pipe. The steam passes around through the coil, past the valve d⁴, which is opened, the cocks f and g in the respective pipes F and G being closed. The water coming in through the pipe H is met by the steam coming from the pipe d³, the cock e² being open. The steam mingling with the water, heats the latter almost to the boiling point and it is sprayed into the pan A. As the water rises, it contacts with the pipe D which contains the live steam and the water is boiled. The object of spraying the water into the tank is to

get the water in fine streams and to permit the air to pass out of it more readily. The boiling of the water serves to drive off the remaining air and the steam and air driven off pass out of the pipe C. As the water rises, it lifts the float W and upon rising further, flows into the tank K, from whence it may be drawn off at will. As the tank K fills, the oil which may be carried over 10 with the water, rises to the top and passes through the opening t into the receptacle T, and thence by the pipe t' into the sewer. The valve M prevents the water from flowing into the tank K too rapidly, for as the 15 water lowers in the tank A, the float descends and the valve closes the pipe L, and only opens it again when enough water has entered the pan A. This prevents the water from entirely leaving the pan and, therefore, the loss of heat if the coils of the pipe D should be left exposed.

In case the water is to be heated with the exhaust steam, the cock e² is closed and the cocks f and g are opened. The exhaust 25 steam coming from the pipe G heats the water and sprays it into the pan A, while

the live steam may be used exclusively for boiling the water. This steam now passes out through the pipe F to the exhaust.

I am aware that other devices, similar in 30 their nature, might be made but I consider as my own all such modifications as fairly fall within the spirit and the scope of the invention.

I claim:—

In a reboiler, a receptacle, a spraying device disposed therein, a water pipe leading to said spraying device, a live steam coil disposed in the bottom of said receptacle and having an upwardly extending pipe 40 communicating with the spraying device, a cock for cutting off communication of the steam pipe with said spraying device, and an exhaust steam pipe communicating with said spraying device and provided with a 45 cock for cutting off communication therewith.

CLAUD G. CARLEY.
